PLATEN ROLL FOR WRITING MACHINES

Albert W. Metzner, Dayton, Ohio, assignor to The Standard Register Company, Dayton, Ohio, a corporation of Ohio

Application September 11, 1933, Serial No. 688,936

21 Claims. (Cl. 197—133)

This invention relates to platen rolls for writing machines, and more particularly to a platen roll especially adapted for manifolding purposes about which writing material may be fed past writing position by either positive feeding devices or by frictional feeding means.

Platen rolls of the present construction are intended for use in typewriters, computing machines, billing machines, and analogous apparatus, and are made in suitable sizes and proportions corresponding to the original or standard platen rolls of such machines for which the present rolls are to be interchanged. The present platen roll comprises a plurality of sections between which are interposed pin wheel units, the material feeding pins of which are progressively extended and retracted in unison with the rotation of certain of the platen roll sections. The pin wheel units are further adjustable to present the projecting pins alternately in effective and ineffective positions, such alternations being effected in unison with the partial rotary motion of another of the platen roll sections from one position to another. The feeding pins are adjusted to ineffective position when the platen roll is to be used for frictional feeding of the writing material at which time the pin wheel unit is masked at the writing position by an overlying portion of one of the sections brought to a position coincident with the writing line simultaneously with the adjustment of the pins to their ineffective positions, to afford a continuous flush impact surface for the imprinting type.

The object of the invention is to simplify the construction as well as the means and mode of operation of writing machine platens, whereby they will not only be cheap in construction, but will be more efficient in use, capable of application to a wider variety of record material and for different purposes, easily controlled and adjusted for different conditions of use, and unlikely to get out of order.

A further and important object of the invention is to provide a platen roll capable of being substituted for the usual platen roll of a type-writing machine, computing machine, billing machine or analogous apparatus by which an ordinary commercial typewriter may be quickly and easily converted into a billing machine, and whereby various forms of commercial computing, billing, and writing machines may be readily adapted for manifolding multiple copies which are positively fed past writing position and maintained accurately in registering relation with each other.

A further object of the invention is to provide an improved platen roll which is readily and quickly convertible from positive feeding condition and vice versa.

A further object of the invention is to provide a pin type feeding device which can be readily and quickly transformed to facilitate frictional feeding of unpunched paper of greater width.

A further object of the invention is to provide a mask or shield for pin type platen rolls by which a continuous flush tympan or impact surface is afforded at the writing position when the pins are adjusted to inoperative position.

A further object of the invention is to provide means for presenting a smooth writing area over the positions of pin type feeding devices when the latter are retracted and to provide common adjusting means for the feeding pins and the mask or shield.

A further object of the invention is to provide a platen roll having positive material engaging devices which may be substituted for the regular or standard platen rolls of writing machines without conflicting or interfering with adjacent structural parts of the writing machine.

With the above primary and other incidental objects in view, as will more fully appear in the specification, the invention consists of the features of construction, the parts and combinations thereof, and the mode of operation, or their equivalents, as hereinafter described and set forth in the claims.

In the accompanying drawing, wherein is shown the preferred but obviously not necessarily the only form of embodiment of the invention, Fig. 1 is a perspective view of a writing machine platen roll, embodying the present invention, wherein the pin wheel units have been adjusted to present the reciprocating pins in an ineffective feeding position, and the platen roll sections correspondingly relatively adjusted to present the shield or extension across the pin wheel units in writing position to afford a continuous flush writing surface. Fig. 2 is a similar view of a portion of the platen roll, showing the parts adjusted to alternate positions, wherein the shield extensions have been moved out of writing position and the pin wheel units adjusted to present the feeding pins in their effective positions. Fig. 3 is a side elevation of a portion of the platen roll, showing the relation of the respective sections to the frictional feeding rollers of a conventional writing machine. Fig. 4 is an end view of the platen roll and contiguous coacting parts of a writing machine platen car.

riage with the feeding pins adjusted to their effective positions. Fig. 5 is a similar view, wherein the pin wheel unit has been adjusted to present the feeding pins in an ineffective relation with the writing material. Fig. 6 is a longitudinal sectional view of a portion of the platen roller. Fig. 7 is a similar view, showing the sections of the platen roll relatively separated.

Like parts are indicated by similar characters 10 of reference throughout the several views.

The present platen roll is intended to be interchangeably substituted for the usual platen roll of a writing machine, such as a typewriter, computing machine, billing machine, or analogous 15 device, for the purpose of adapting such writing machine to feed the writing material alternately by positive engagement of traveling feeding pins engageable in marginally punched holes in the material and to feed unpunched material by the usual frictional feeding means found 20 in such writing machines, and to afford a continuous uninterrupted writing surface. The writing machine roll, forming the subject matter hereof, comprises multiple sections of which 25 only two sections 1 and 2 have been shown in the drawing, but which may be extended to include additional sections. The section 1 is firmly secured to the rotary shaft 3 for unison rotation therewith, as, for example, by means of the 30 terminal head 4 having therein a set screw 5, as shown in Fig. 1. Obviously other methods of connecting the roll section with the shaft may be employed. The shaft 3 is mountable in the usual journal bearings of a writing machine carriage 6, in which the present platen roll is interchangeably mountable with the standard smooth frictional feeding platen roll with which such machines are ordinarily equipped.

Located in the opposite ends of the cylindrical sleeve, comprising the section 1 of the platen roll, are pin wheel units, each comprising a head 4 having therein radially disposed guides 7, in which are located reciprocating feeding pins 8 which are progressively projected beyond the periphery of the platen roll and then retracted interiorly thereof in unison with the rotation of such platen roll section 1. To effect such progressive reciprocation of the feeding pins, there is associated with each of the pin wheel units an eccentric cam 10 which is normally stationarily held in adjusted position and which is provided with a lateral flange 11 engaging in lateral notches 12 in the reciprocating pins 8. As the platen roll section rotates the pins 8 travel about the eccentric flange of the cam 10 and are thereby given to and fro motion in radial direction by which the tapered extremities of the feeding pins are projected beyond the periphery of the roll as the pins pass about the eccentric side of the cam 10 and are retracted within the periphery of the roll as they pass therebeyond onto a concentric portion of the cam flange. Whether the pins 8 are presented in an effective position wherein they will engage in marginally punched holes in the writing material 12 or whether they will be projected from the platen roll in such position that they will be ineffective to engage the writing material depends entirely upon the relative rotative position of the cam 10, which 70 may be rocked from the position shown in Fig. 4 to that shown in Fig. 5 and vice versa. To effect such rocking motion, the pin actuating cams 10 are fixedly secured by pinning or otherwise to a rock sleeve 13 mounted concentrically with the shaft 3 and extending through the respective

sections 1 and 2 of the platen roll and beyond the extremity of the latter where the sleeve 13 carries a notched disc 14.

The disc 14 has an undulating or crenate periphery by which it may be more easily grasped to rock or partially rotate the tubular sleeve or shaft 13 and thereby rock the cams 10 to alternate positions. The cam 10 and sleeve 13 are held in their adjusted position by means of a detent plunger 15 engageable in either one of two peripheral notches 16 in the adjusting disc 14. The detent plunger 15 is carried upon a lateral ear 17 projecting from a disc 18, which in turn is fixedly engageable in any one of several rotative positions with a second disc 19 from which projects a bifurcated arm 20 straddling a frame rod 21 of the writing machine platen carriage.

The rotative adjustability of the discs 18 and 19 relative to each other is for the purpose of 20 readily accommodating the device to writing machines of different manufacture wherein the accessible frame rod 21 may be differently positioned, and also to enable the operative and inoperative positions of the pins to be varied to 25 accommodate writing machines of different character or manufacture.

The particular pin wheel unit and the specific adjusting means therefor form no part per se of the present invention, but are more fully described and are claimed in a companion application Serial No. 542,855, filed June 8, 1931.

The second section 2 of the platen roll is mounted concentrically with the section 1 and is fixedly secured upon the rock sleeve 13 which also carries the pin control cams 10. The section 2 is provided with a lip or extension 22 which overlaps the pin wheel unit 4 and is movable into and out of writing position by the partial rotation of the sleeve 13, which simultaneously rocks the pin control cams 10 to cause the feeding pins 8 to be projected at an ineffective position, as is illustrated in Fig. 5. The extension or lip 22, upon the platen roll section 2, bridges the intermediate pin wheel unit and forms a continuous uniform writing surface thereacross when the feeding pins 8 are adjusted to their ineffective positions. Being positively connected to the sleeve 13 for unison rocking motion, the extension lip or mask 22 and the feeding pins 8 alternate at the writing line, one being moved into such operative position as the other is shifted therefrom.

When the feeding pins 8 are projected at their effective position, as is shown in Fig. 4, the friction rolls 23, ordinarily provided in writing machines for cooperation with the platen roll, are adjusted to their retracted or inoperative position by operation of the usual finger lever 25 found on conventional writing machines. This adjustment of the friction rolls 23 toward and away from the platen roll by means of the finger lever 25 is an adjustment ordinarily provided upon writing machines of the typewriter or computing machine style. When it is desired to feed unpunched writing material by frictional feeding means, the finger lever 25 is adjusted to bring the friction rolls 23 into feeding contact with the periphery of the platen roll section 1. Whether the writing material is fed frictionally by the coaction of the platen roll section 1 and the frictional feeding rolls 23 or fed positively by the operation of the pin wheel units, only the platen roll section 1 rotates and the shorter section 2 remains stationary in its adjusted position. For this reason the section 2 of 75

the platen roll is of slightly reduced diameter except throughout the segmental portion coincident with the lip or mask extension 22, whereby a slight clearance is provided between the periphery 5 of the platen roll section 2 and the underlying portions of the frictional rollers 23. Some types of writing machines are provided with additional frictional rollers located above the platen roll and to accommodate such construction the section 10 2 of the platen roll may, if desired, be provided with an indentation 26 in one side thereof, positioned to coincide with and afford clearance for the overlying friction rolls.

The platen roll sections 1 and 2 are independently adjustable about the common shaft 3. The rotation of the platen roll section 1 carries with it the series of feeding pins 8 which are thereby caused to travel about the eccentric cam flange 11 and are reciprocated thereby to progressively project the pins beyond the periphery of the platen roll at such radial position as may be determined by the rocking adjustment of the cam 10. The section 2 of the platen roll is likewise adjustable relative to the section 1 and by its adjustment it 25 changes the position of the cam 10 from that shown in Fig. 4 to that illustrated in Fig. 5, and vice versa, thereby changing the effective position at which the pins are projected. The disc 14 being also connected to the rock sleeve 13 30 to which the section 2 is fixedly connected, the engaging detent 15 serves to hold the section 2 in its adjusted position. When adjusted to present the cam 10 in the position shown in Fig. 5 whereby the pins will be projected in ineffective 35 position, the mask extension or lip 2 is positioned at the writing line in overlapping relation with the pin wheel unit and serves to close the pin openings therein and present a flush uniform writing surface. This enables the use of unpunched 40 paper which may be of greater width than the distance between the pin wheel units.

From the above description it will be apparent that there is thus provided a device of the character described possessing the particular features 45 of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to 55 the specific features shown, but that the means and construction herein disclosed comprise the preferred form of several modes of putting the invention into effect, and the invention is therefore claimed in any of its forms or modifications within 60 in the legitimate and valid scope of the appended claims.

Having thus described my invention, I claim:

1. A platen roll for writing machines including axially aligned cylindrical sections mounted for 65 independent rotary motion of one section relative to the other, a pin wheel unit associated therewith, material engaging pins carried by the unit and adjustable to present the pins in effective and ineffective relation with writing material 70 associated with the platen roll, and an extension upon one of the sections overlapping the pin wheel unit and movable into and out of writing position to afford a continuous uniform writing surface across the pin wheel unit when the pins 75 are in ineffective relation.

2. A platen roll for writing machines including axially aligned cylindrical sections mounted for independent rotary motion of one section relative to the other, a pin wheel unit interposed therebetween, material engaging pins carried by the unit and adjustable to present the pins in effective and ineffective relation with writing material associated with the platen roll, an extension upon one of the sections overlapping the pin wheel unit and movable into and out of writing position to 10 afford a continuous uniform writing surface across the pin wheel unit when the pins are in ineffective relation, and means common to the pins and extension carrying section for alternating the operative relation of the pins and extension with the writing material. 15

3. A platen roll for writing machines including axially aligned cylindrical sections mounted for independent rotary motion of one section relative to the other, a pin wheel unit associated therewith, material engaging pins carried by the unit and adjustable to present the pins in effective and ineffective relation with the writing material associated with the platen roll, and an extension on one of the sections overlapping the pin wheel unit 20 to 25 form a continuous uniform writing surface thereacross.

4. A writing machine platen including relatively revoluble axially aligned sections, a pin wheel unit associated with the sections, retractable material feeding pins in said unit, and means for progressively retracting and extending the feeding pins in unison with the relative rotation of the respective platen sections. 30

5. A writing machine platen including relatively revoluble axially aligned sections, a pin wheel unit interposed between the sections, retractable material feeding pins in said unit, means for progressively retracting and extending the feeding pins in unison with the relative rotation of the respective platen sections, and an extension on one of the sections overhanging the pin wheel unit to afford a continuous writing surface when the pins at such point are withdrawn. 35 40

6. A writing machine platen roll including relatively rotatable sections, a pin wheel unit associated with the sections, retractable and extendible material feeding pins mounted in said unit, means for retracting and extending the pins by relative rotation of one of the sections, and 45 means for circumferentially changing the positions of extension and retraction of the pins by rotation of another section. 50

7. A writing machine platen including relatively rotatable sections, a pin wheel unit interposed between the sections, material feeding pins carried thereby adjustable to operative and inoperative position by the rotation of one of said sections, and an extension on said section overhanging the pin wheel unit and adjustable into and 55 out of writing position alternately with the material feeding pins. 60

8. A writing machine platen including relatively rotatable sections, a pin wheel unit associated with the sections, material feeding pins carried thereby, means for progressively extending and retracting said pins by the rotation of one of the sections, and means for circumferentially changing the operative and inoperative positions of extension of the pins by the rotation of 70 another section. 65

9. A writing machine platen including relatively rotatable sections, a pin wheel unit interposed between the sections, material feeding pins carried thereby adjustable to operative and in- 75

- operative positions, and an extension on one of the sections overhanging the plane of operation of the pins and adjustable into and out of operative position alternately with the pins.
5. 10. A writing machine platen including relatively rotatable sections, a pin wheel unit associated with the sections, material feeding pins carried thereby adjustable to operative and inoperative positions, and an extension on one of the sections movable into and out of writing position simultaneously with the movement of the pins into and out of inoperative position.
10. 11. A writing machine platen roll including relatively revoluble sections, a pin wheel unit associated therewith, radially reciprocator material feeding pins carried thereby having effective and ineffective positions of operation, means operative by the relative rotation of one section for reciprocating the pins, and means effective by rotation of another section for determining the effective and ineffective positions of operation of the pins.
15. 12. A platen roll for a writing machine adapted for alternate positive and frictional feeding of writing material, including a plurality of roll sections, material feeding pins associated therewith and adjustable to effective and ineffective positions of operation, friction rollers engageable with one of said sections independently of another section thereof, one of said sections having an extension thereon bridging the pin wheel unit in proximate relation with the adjacent section.
20. 13. A writing machine platen including relatively revoluble axially aligned sections, a rotary pin wheel unit associated with the sections, extendible and retractible material feeding pins in said unit, means for progressively extending and retracting the pins in unison with the rotation of one section, and means for effecting extension and retraction of the pins at different positions in accordance with the rotative adjustment of the other section.
25. 14. A writing machine platen including relatively revoluble axially aligned sections, a rotary pin wheel unit interposed between the sections, extendible and retractible material feeding pins in said unit, progressively extendible and retractible at different points in their path of rotation and control means by which the progressive extension and retraction of the pins is governed by the rotary adjustment of one section and the position of rotary travel at which such extension and retraction occurs is governed by the rotary adjustment of the other section.
30. 15. A writing machine platen including a plurality of relatively rotatable sections, a series of retractible feeding pins carried by one of the sections, means for effecting the extension of the retractible pins at different relatively spaced points and a shield carried by another section and overlying one position of projection of the pins when such pins are being projected at a different point.
35. 16. A writing machine platen including a plurality of relatively rotatable sections, a series of retractible feeding pins carried by one of the sections, a shield carried by another section for overlying the position at which such pins are projected, and control means for alternating the position of the shield and that at which the retractible pins are projected.
40. 17. A writing machine platen including a plurality of relatively rotatable sections, a series of retractible feeding pins carried by one of the sections and projectable into operative position substantially at the writing line of the machine, a shield carried by another section of the platen and movable into and out of like position at the writing line, and control means for alternating the feeding pins and the shield at the writing line.
45. 18. A writing machine platen including a plurality of relatively rotatable sections, a series of retractible feeding pins carried by one of said sections extendible in offset relation with the writing line of the platen, and a shield carried by another of said sections and operable in the writing line of the platen to afford a continuous writing surface past the position of the pins.
50. 19. A writing machine platen including relatively revoluble axially aligned sections, at least one section being adapted for continuous rotary movement and another section for partial rotary movement, a pin wheel unit interposed between the sections, retractible material feeding pins in said unit, and means for progressively retracting and extending the feeding pins in unison with the relative rotation of one of the sections.
55. 20. A writing machine platen including relatively rotatable sections, a pin wheel unit associated with the sections, material feeding pins carried thereby adjustable to operative and inoperative position, an extension on one section overhanging the pin feed device, and means common to the sections for simultaneously changing the relative positions of the pins and overhanging section with regard to the writing position of the machine.
60. 21. A writing machine platen including relatively rotatable sections, a pin wheel unit interposed between the sections, material feeding pins carried thereby adjustable to operative and inoperative positions, and an extension on one of the sections movable into and out of writing position simultaneously with the movement of the pins into and out of inoperative position, one section being adapted for continuous circumferential operation and another section having a limited movement of less than a complete cycle of the platen circumference.

ALBERT W. METZNER. 60
